Specification of Letters Patent.

Patented Jan. 3, 1922.

Application filed April 7, 1920. Serial No. 371,837.

To all whom it may concern:

Be it known that I, SAMUEL HOLLINGSWORTH, a citizen of the United States, and resident of Scotch Plains, Union County, New Jersey, have invented new and useful Improvements in Intaglio-Printing Machines, of which the following is a specification.

The present invention relates generally to intaglio printing machines of the type shown in patent to Sturtevant, No. 1146290, of July 13, 1915, and has more particularly reference to the driving means that advance the planks and change its direction at right angle to its previous line of travel.

In machines of this general type there is generally a number of angularly disposed tracks, usually arranged at right angles to each other, and a number of "planks" or plate carrying members are provided, usually four, that travel on the tracks and have their direction of movement changed, at right angles to the preceding one, when the end of each track is reached. The drive of the plank is usually effected by means of a sprocket chain passing over four sprockets, and heretofore difficulty has been experienced in changing the direction of movement of the plank at the end of each track, in that the sprocket chain has a tendency to slip with respect to or to disengage the sprocket and it is therefore difficult to control the plank as it passes from one track to another.

The main object of this invention is to provide means that will adequately control a plank as it passes from one track to another, and it consists in the hereinafter described features of construction.

In the accompanying drawings the invention is embodied in a concrete and preferred form in which:

Fig. 1 is a plan view of a machine of the general type to which this invention relates, showing the angularly disposed tracks and the four planks together with the driving means for the latter, the superstructure of the machine being omitted.

Fig. 2 is a plan view of one corner of the device shown in Fig. 1, with a plank indicated in dotted lines.

Fig. 3 is a vertical sectional view on the line 3-3 of Fig. 2.

Fig. 4 is a vertical sectional view on the line 4-4 of Fig. 2.

1 indicates the frame of the machine provided with four angularly disposed tracks 2, 3, 4 and 5, on which travel four planks 6, 7, 8 and 9. At each corner of the machine is an upright shaft respectively designated by 10, 11, 12 and 13, which are geared together by the usual means (not shown), and each of said upright shafts is provided with a sprocket wheel 14 over which is trained the sprocket chain 15 having four pins 16, each of which is in free engagement with an oversize opening 17 at the central point of a plank. It will be understood that the pins on the chain advance the planks on the tracks aforesaid.

In order to effectively control each plank, as it changes its path of movement from one track to another, I provide an auxiliary driving device whose surface speed is equal to that of the pin on the chain that temporarily engages each plank on the turn so as to positively carry the plank from one track to another. This device locks itself automatically to the plank and automatically unlocks itself from and disengages the plank.

As here shown this auxiliary driving device is conducted as follows: 18 is an upright shaft rotating at the same speed as one of the upright sprocket shafts, say in this instance 12, and driven therefrom by spur gears 19, 20 and 21. At its upper end shaft 18 carries a head 22 in which is pivotally supported, by means of suitable ears 23, a rocker arm 24, one end of which engages latch or taper pin 25 sliding in guide 26 and normally held in a depressed position by means of stationary cam surface 27, acting on cam roller 28 carried by rocker arm 24.

At a certain point in its revolution roller 28 drops into a depression or hole 29 in said cam 27 and a suitable spring, here shown as a helicoidal spring 30, is free to move rocker arm 24 and pin 25 is thereby projected from its retracted position. Each plank is provided with four openings 31, one of which coincides or registers with taper pin 25 when it is moved into the projected position. The surface speed of the pin 25 is equal to the surface speed of pin 16; that is to say: the distance from the center of rotating shaft 18 to the center of pin 25 is the same as the distance from the center of sprocket wheel 14 to the pitchline of said sprocket wheel. It is also to be noted that the radius of curved

surface 32 at the corner of central spacing member 33, against which surface the plank bears during its period of transfer from one track to another, is the same as the radius 5 from the center of shaft 18 to the center of pin 25. When the plank has turned the corner at 32, roller 28 will again engage cam surface 27 and, acting in opposition to spring 30, will retract pin 25 from opening 10 31, thereby releasing the plank.

It will be understood that by the foregoing means, the auxiliary driving device moves the plank in synchronism with the movement imparted by the chain and also 15 locks the plank temporarily against outward displacement, so that chain 15 and sprocket wheel 14 will remain in proper mesh. If desired there may be two of these locking devices at each turn in the bed, said locking 20 devices being at diametrically opposite sides of shaft 12. Since the two devices are identical in construction there is no need of repeating the description; suffice it to say that both shafts 18 rotate at the same speed in 25 the same direction and both are driven from shaft 12.

I claim:

1. In a printing machine, a plurality of angularly disposed tracks, a plank for 30 traversing said tracks, a rotatable transmission member, a flexible transmission member actuated thereby and engaging the plank to advance it over the tracks and to transfer it from one angularly disposed track to another, a second rotatable member rotating in the same direction as the first rotatable member, a normally retracted pin carried by said second rotatable member having the same surface speed as that of the pitch diameter 35 of the first rotatable member, and means for projecting said pin into engagement with the plank during the period of its transfer from one track to another.

2. In a printing machine, a plurality of

angularly disposed tracks, a plank for 45 traversing said tracks, a rotatable transmission member, a flexible transmission member actuated thereby and engaging the plank to advance it over the tracks and to transfer it from one angularly disposed track to another, two additional rotatable members disposed at diametrically opposite sides of the first rotatable member and both rotating in the same direction as said first rotatable member, a normally retracted pin carried by each of said additional rotatable members, said pin having the same surface speed as that of the pitch diameter of said first rotatable member, and means for projecting said pin into engagement with the plank 50 during the period of its transfer from one track to another.

3. In a printing machine, a plurality of angularly disposed tracks, a plank for 55 traversing said tracks, a rotatable transmission member, a flexible transmission member actuated thereby and engaging the plank to advance it over the tracks and to transfer it from one angularly disposed track to another, a second rotatable member rotating in 60 the same direction as the first rotatable member, a normally retracted pin carried by said second rotatable member having the same surface speed as that of the pitch diameter 65 of the first rotatable member, and means for projecting said pin into engagement with the plank during the period of its transfer from one track to another, and a curved surface connecting adjacent tracks and against 70 which the plank bears during its period of transfer, said curved surface being drawn on a radius equal to a radius drawn from the center of the second rotatable member to the center of the pin.

Signed at Scotch Plains, in the county of 85 Union and State of New Jersey, this second day of April 1920.

SAMUEL HOLLINGSWORTH.
